UNITED STATES PATENT OFFICE.

WILLIAM FARRELL FULTON, OF SHREVEPORT, LOUISIANA, ASSIGNOR TO PALMER CORPORATION, A CORPORATION OF DELAWARE.

APPARATUS FOR THE PRODUCTION OF CARBON BLACK.

Application filed May 31, 1927. Serial No. 195,420.

The present invention relates to improvements in apparatus for the production of carbon black, and more particularly the invention refers to the manufacture of a commercial carbon black from natural gas and other hydro-carbon vapors.

An object of the invention is to produce a carbon which will not be gray in color, but which will be of a commercial grade without the necessity of subjecting the carbon, after production, to subsequent processes.

A further object of the invention is to provide an improved apparatus for the production of carbon rapidly and economically, in which the hydrogen gas evolved during the process is utilized for the production of heat necessary in the process of making the carbon from the natural gas or hydro-carbon vapors.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a top plan view with parts broken away, showing an improved apparatus for carrying out the present invention.

Figure 2 is a longitudinal central vertical section taken on the line 2-2 in Figure 1.

Figure 3 is a horizontal section taken on the line 3-3 in Figure 2.

Figure 4 is a transverse vertical section taken on the line 4-4 in Figure 2, and

Figure 5 is a cross section taken on the line 5-5, also in Figure 2.

Referring more particularly to the drawings, 6 designates a rotatable collector cylinder on the exterior surface of which the carbon black is adapted to be deposited. This cylinder is arranged to receive the cold gas through the inlet pipe 7 under the control of a valve 8. The inlet pipe 7 extends through a cylinder head 9 which is affixed as by the screws or other fastenings 10 to one end of the collector cylinder 6. The head 9, or the cylinder, is provided with a sprocket 11 for receiving the chain 12 by which the collector cylinder is subjected to a constant rotary movement. The chain is driven by a sprocket 13 on a shaft 14, having the pulley 15 engaged by the drive belt 16.

This belt is driven from any appropriate source of power and the pipe 7 is connected with a source of supply of the natural gas or hydrocarbon vapors.

The cylinder 6 is mounted within a furnace, retort or heating chamber 17 and is provided with the outlet pipe 18 for the heated gas, which extends through the opposite removable head 19 of the collector cylinder 6. This collector cylinder may be mounted upon appropriate bearings or it may rotate upon the pipe ends. The gas outlet pipe 18 extends up through the chimney or flue 20 and connects with a down-comer coil 21 having the lower branch 22 extending through the side of the stack 20 and connecting with the vertical pipe 23. A by-pass 24 is shown as connected between the upper end of the pipe 18 and the vertical pipe 23 for cutting out the coil 21. A normally closed valve 25 is disposed in this by-pass.

The pipe 23 communicates at its lower end with the branch pipes 26 and 27, which connect with the two manifolds 28 and 29 mounted in or at the sides of the refractory arches 30 and 31. The manifolds 30 and 31 are mounted upon the refractory bed or base 32 of brick or other appropriate material in which the lower half portion of the combustion tube 33 is centrally mounted. The upper half of this combustion tube extends up between the refractory arches 30 and 31, which are shaped into arch form to conform substantially with the contour of the tube 33 and to provide narrow passages 34 and 35 between the tube and arches at opposite sides. Within the arches are passages 36 and 37 connecting with the manifolds 28 and 29. The inner terminal ends of the passages 36 and 37 are given an upward inclination as shown at 38 and 39.

The combustion tube 33 is supplied in suitable quantity with refractory particles 40 on which is impressed and retained a high heat supplied by the burner 41. This burner receives oxygen through a pipe 42 under the control of a valve 43 in the form of air, steam or the like and hydrogen is supplied to the burner 41 by the pipe 44, which connects by means of various branches 45 with the ridge portion of the convergent roof 46 of the retort. The combustion tube 33 connects also with the stack 20, which is appropriately mounted in the bed. A scraper 47

is arranged to remove the carbon from the collector cylinder 6 and the scraper is disposed on an inclination, whereby the removed carbon will slide down the upper surface of the scraper blade into a trough 48 along which it is advanced by the spiral or other conveyor 49 to a suitable depository.

In the use of the apparatus the gas entering through the pipe 7 to the end 9 of the 10 collector cylinder 6 will itself tend to cool the collector cylinder, but will become highly heated from the heat emanating from the combustion tube 33 below. The heated gas passes out through the outlet pipe 18 and in- 15 to the coil 21, also heated, by the products of combustion passing up through the stack 20. From the coil 21 the highly heated gas is circulated to the two opposite manifolds 28 and 29 and from thence to the numerous 20 passages 37. The gas issues in jets from the up-turned ends 38 and 39 of these transverse passages and merges into a thin stream or sheet within the narrow space between the upper portion of the combustion tube 33 and 25 the arches 30 and 31, the arches guiding the heated gas toward the central opening between the arches and up against the collector cylinder 6, which is disposed directly above this opening. In this zone 30 the gas is decomposed to carbon and hydrogen. The carbon deposits upon the outer surface of the collector cylinder 6 which is in rotary motion, while the hydrogen escapes upwardly and is carried by the 35 pipe 44 to the burner 41 in the combustion tube 33. The carbon is scraped from the collector cylinder 6 by the blade 47, is deposited in the trough 48 and conveyed to its destination by the conveyor 49. The insulation 32 drives the heat in the refractory tube to the upper half of the tube against which the gas impinges. The flow of heat within the combustion tube 33 will be at right angles to the direction of movement of the thin layer of gas or vapor in the 45 spaces 34 and 35. This relatively right angular movement and the velocity of the gas results in the production of a carbon which is cool, which passes out of the heated zone 50 at high velocity and the burning or hardening of the carbon is thus prevented. The carbon is promptly scraped from the rotating collector cylinder 6 upon which it de- 55 posits and is removed before injury. The result is the production, in the single process, of a carbon of commercial grade not gray in color.

This superior grade of carbon black, formed in a very small area and rapidly 60 passed to a cooler zone to prevent burning or destruction of its commercial properties, is produced in a very short time by the improved process and in an inexpensive way by the improved apparatus. The arrangement is such that higher yields of decomposi-

tion are effected. The gas to be decomposed does not come in contact with the burned gas or products of combustion which produces a superior fuel for heating the combustion cylinder. The collector cylinder is 70 heated and the gas is passed at right angles over the outside of this heated cylinder whereby to secure the maximum deposit effect.

It is obvious that various changes and 75 modifications may be made in the details of construction and design of the above specifically described embodiment of this invention without departing from the spirit thereof, such changes and modifications being re- 80 stricted only by the scope of the following claims.

What is claimed is:—

1. An apparatus for the production of 85 carbon black comprising a rotary collector cylinder having communication with a source of gas supply and for heating the gas, manifolds for receiving the heated gas from said collector cylinder, arches having passages for receiving the gas from the 90 manifolds, a substantially horizontal combustion tube between said arches and forming therewith curved thin combustion spaces opened and communicating at the upper 95 portions for directing the decomposed gases at substantially right angles against the rotary collector cylinder.

2. An apparatus for the production of 100 carbon black comprising a rotary collector cylinder having communication with a source of gas supply and for heating the gas, manifolds for receiving the heated gas from said collector cylinder, arches having passages for receiving the gas from the manifolds, a substantially horizontal combustion tube between said arches and forming therewith curved thin combustion spaces open and communicating at the upper portions for directing the decomposed gases at substantially right angles against the rotary 110 collector cylinder, a scraper bearing against said rotary collector cylinder for removing the carbon, and a conveyor positioned to receive the carbon from the scraper and carry same to the destination.

3. An apparatus for the production of 115 carbon black comprising a rotary collector cylinder having communication with a source of gas supply and for heating the gas, manifolds for receiving the heated gas from said collector cylinder, arches having passages for receiving the gas from the manifolds, a substantially horizontal combustion tube between said arches and forming therewith curved thin combustion spaces 120 opened and communicating at the upper portions for directing the decomposed gases at substantially right angles against the rotary collector cylinder, a scraper blade disposed in contact with the rotary collector cylinder, 125

said scraper blade being disposed on an inclination, a trough at the lower portion of the blade for receiving the scraped carbon, and a conveyor extending through the trough for conveying the removed carbon to the destination.

4. An apparatus for the production of carbon black comprising a retort, a rotary collector cylinder therein in communication with a source of gas supply, a substantially horizontal combustion tube extending through the retort below the collector cylinder, a refractory base in which the combustion tube is partially set in, a stack connecting with one end of the combustion tube, a burner connecting with the other end of the combustion tube, refractory pieces in

said tube, a conduit placing the upper portion of said retort in connection with the burner, means for supplying oxygen to the burner, arches on the base within the retort closely spaced from the upper portion of the tube and forming therewith narrow combustion spaces, a coil in the stack in communication with the outlet of the collector cylinder, manifolds at the sides of the arches, said arches having passages communicating with the manifolds and having up-turned ends connecting with the combustion spaces, said combustion spaces merging together upwardly above the tube and beneath the cylinder and having communication with the cylinder.

WILLIAM FARRELL FULTON.
